[57] CLAIM

The ornamental design for a vending machine, as shown and described.

DESCRIPTION

FIG. 1 is a top front left side perspective view of a vending machine showing our new design;

FIG. 2 is a left side elevational view thereof;

FIG. 3 is a right side elevational view thereof;

FIG. 4 is a front elevational view thereof;

FIG. 5 is a top plan view thereof;

FIG. 6 is a rear elevational view thereof; and

FIG. 7 is a bottom plan view thereof.

The portions shown in broken lines are disclosed for illustrative purposes only and form no part of the claimed design.
